UNITED STATES PATENT OFFICE.

THOMAS W. ANDERSON, OF SEALE, ALABAMA.

MAIL-BOX.

No. 899,781.

Specification of Letters Patent. Patented Sept. 29, 1908.

Application filed May 13, 1908. Serial No. 432,677.

To all whom it may concern:

Be it known that I, THOMAS W. ANDERSON, a citizen of the United States, residing at Seale, in the county of Russell and State of Alabama, have invented a new and useful Mail-Box, of which the following is a specification.

This invention relates to mail boxes such as used upon rural free delivery routes, and 10 more particularly to supports for the boxes.

The object of the invention is to provide a box support designed to normally hold the box at a predetermined elevation but which can be drawn downward to permit the box 15 to be swung into the vehicle in which the carrier is located. It thus becomes possible to remove mail from and place it into the box in wet weather without requiring the carrier to leave the vehicle and thus become exposed to the elements.

Another object is to provide a box support which shall automatically return the box to raised position as soon as the carrier releases it.

With these and other objects in view the invention consists of certain novel features of construction and combinations of parts which will be hereinafter more fully described and pointed out in the claims.

In the accompanying drawings is shown 30 the preferred form of the invention.

In said drawings—Figure 1 is a side elevation of a support embodying the present improvements, the same being shown in dotted lines in lowered position. Fig. 2 is an edge view of the base portion of the support, parts thereof and of the post being broken away. Fig. 3 is an edge view of the upper portion of the support and its connection with the box. Fig. 4 is a longitudinal section through the arms of a modified form. Fig. 5 is a transverse section therethrough.

Referring to the figures by characters of reference, A designates a post, preferably 45 three or four feet in height, and designed to be located at the side of a road. The mail box B, which can be of any preferred construction, is designed to be connected to the post by means of the support constituting 50 the present invention. This support consists of a base plate 1 secured by means of screws or in any other suitable manner to the top of a post A, and resting upon this base plate is a disk 2 having a stud 3 extending downward 55 from the center thereof and mounted to rotate in the center portion of the plate 1.

Secured upon this disk 2 are oppositely-disposed angular brackets 4 spaced apart a suitable distance to receive parallel arms 5 and 6. These arms are disposed in the same plane 60 and are of the same length. The arm 5, however, is pivoted to the brackets 4 at a point nearer the disk 2 than is the arm 6. Both of the arms are held normally in contact by means of a coiled spring 7 arranged 65 diagonally upon one face of the two arms and connected to said arms in any preferred manner adjacent opposite-ends thereof. This spring is constantly under stress and therefore tends to hold the two arms pressed together and consequently in an upright position. Secured to the bottom of the box B are oppositely-disposed angular brackets 8, and the two arms 5 and 6 project between 70 the brackets and are mounted on pivots 9, 75 the pivot of the arm 6 being arranged nearer the box than the pivot of the other arm. In other words, the distance between the two pivots of each arm is the same. A chain or other flexible actuating device 10 is secured 80 to the brackets 8 and is preferably provided at its free end with a ring 11.

As heretofore stated, the spring 7 holds the arms 5 and 6 normally pressed together and the box B is therefore normally supported by 85 the arms directly above the post A. When the mail carrier desires to place the mail within or remove it from the box without, however, leaving the vehicle in which he is seated, he may reach out and pull downward 90 on the chain 10. This will cause the two arms 5 and 6 to swing down on their respective pivots thus increasing the stress of the spring 7 but maintaining the box B in an upright position, as indicated by dotted lines 95 in Fig. 1. The lowered arms and the box can then be swung into the vehicle, and after the interchange of mail has been effected the carrier can swing the box out of the vehicle and push upward on the arms, whereupon 100 the tensioned spring 7 will draw the arms back to their normal or upright positions. The support herein described is also advantageous because it serves to hold the box at 105 a greater elevation than would otherwise be possible and, therefore, the danger of injury to the box by passing vehicles is reduced to the minimum.

If preferred, in lieu of forming arms 5 and 6 of flat strips of metal each arm may be 110 formed of a hollow semi-cylindrical member such as one-half of a split tube. The two

- arms, which have been indicated at 12 and 13 in Figs. 4 and 5, when upright, contact so as to form a tubular housing in which the spring 14 is located. This spring is fastened at opposite ends to the respective arms. Otherwise the arms operate in the same manner as do those shown in Figs. 1 and 2. This construction is advantageous because the spring 14 is housed at all times except when the box 10 is in lowered position.
- What is claimed is:—
1. A support for mail boxes comprising revolvably supported base brackets, box-engaging brackets, normally vertical parallel arms 15 pivotally connected at their ends to the base and box-engaging brackets, and an elastic connection between the arms for holding said arms normally in contact and in vertical position.
  - 20 2. A support for mail boxes comprising bottom brackets mounted to rotate in a complete circle, box engaging brackets, parallel arms pivotally connected to the brackets, said arms and brackets being so connected as 25 to maintain the box-engaging brackets at a predetermined angle to the horizontal irrespective of the movement of the arms, and an elastic connection between the arms for maintaining said arms normally vertical and 30 in contact.
  3. A support for mail boxes comprising a disk mounted to completely rotate, brackets upstanding therefrom, box-engaging brackets, parallel arms pivotally connected to the 35 brackets and disposed to maintain the box-engaging brackets at a predetermined angle to the horizontal irrespective of its elevation and the movement of the arms, and elastic means for connecting the arms for maintaining 40 them normally vertical and in contact and means connected to and extending from one of the brackets whereby the support may be actuated.
  4. A mail box support comprising upper 45 and lower brackets mounted to completely rotate, parallel arms pivotally connected to the brackets and mounted to swing vertically, said arms and brackets being so disposed as to maintain the upper bracket in a predetermined relation to the horizontal irrespective 50 of the movement of the arms and of the elevation of the upper brackets, and means for maintaining the arms normally vertical and in contact.

5. A mail box support comprising a base, a disk mounted to completely rotate thereon, a bracket upstanding from the disk, parallel arms pivotally connected to the bracket, yieldable means for holding the arms normally vertical and in contact, and means pivotally connected to the arms for engaging a box.

6. A mail box support comprising a base, parallel pivoted arms mounted to rotate above the base, elastic means for maintaining the arms normally vertical and in contact, said arms being movable against the action of said means in a downward direction, and box-engaging means pivotally connected to the arms and maintained thereby in a predetermined relation to the horizontal during the movement of the arms, the pivots of said means being normally disposed in vertical alinement with the lower pivots of the arms.

7. The combination with a support; of a base plate secured thereon, a disk mounted to rotate upon the plate, a bracket on the disk, parallel arms pivotally connected to the bracket and mounted to swing vertically, a box-engaging bracket pivoted to the arms 80 and coöperating with the first-mentioned bracket to maintain the arms parallel during their swinging movement, elastic means connecting the arms for maintaining them normally vertical and in contact, the pivots of the box engaging bracket being normally disposed in vertical alinement with the lower pivots of the arms, and means connected to one of the brackets to facilitate the actuation 85 of the arms.

8. A mail box support comprising base and box engaging brackets, parallel hollow arms pivotally connected to the brackets and normally contacting at their longitudinal edges, and a spring normally housed between the 95 arms and secured at its opposite ends thereto, said spring constituting means for holding the arms normally vertical and in contact, said arms when in normal position completely concealing the spring.

In testimony that I claim the foregoing as my own, I have hereto affixed my signature in the presence of two witnesses.

THOMAS W. ANDERSON.
